UNITED STATES PATENT OFFICE.

JAMES P. DOOLEY, OF WORCESTER, MASSACHUSETTS, ASSIGNOR TO WRIGHT WIRE COMPANY, OF WORCESTER, MASSACHUSETTS, A CORPORATION OF MASSACHUSETTS.

CONTINUOUS WIRE-DRAWING MACHINERY.

1,286,563.

Specification of Letters Patent.

Patented Dec. 3, 1918.

Application filed March 7, 1917. Serial No. 153,157.

To all whom it may concern:

Be it known that I, JAMES P. DOOLEY, a citizen of the United States, residing at Worcester, in the county of Worcester and 5 Commonwealth of Massachusetts; have invented a new and useful Improvement in Continuous Wire-Drawing Machinery, of which the following, taken in connection with the accompanying drawings, is a specification.

This invention relates to an improvement in that class of wire drawing machinery in which the wire to be drawn is reduced in diameter a number of times by being successively passed through a series of dies in one continuous drawing process, the present application covering the subject matter which is shown and described but not claimed in my application Serial No. 808,691, 15 filed December 26, 1913, which has matured into Patent No. 1,212,919, issued January 16, 1917.

In drawing wire by the continuous process, it has been the practice heretofore to 25 provide adjacent each reducing die of the series, and in position to draw the wire therethrough, a drawing or forwarding drum, the wire being given a number of turns around each of said drums in order 30 to insure of its being forwarded at a speed substantially equal to the peripheral speed of the drum. Each drum of the series is given a greater peripheral speed than the one next preceding, in order to allow for the 35 elongation of the wire due to its reduction in diameter. It sometimes happens, owing to unusual resistance arising in the drawing operation, that the predetermined peripheral speed of one or more of the drums becomes 40 greater than the speed at which the wire is traveling, which condition causes a relative slipping between the wire and drum, resulting in a roughening of the wire and a scoring of the drum. The same detrimental effect 45 is also apparent, when, by reason of an unexpected decrease in one or more of the resistances to the drawing operation, the speed at which the wire is traveling exceeds the peripheral speed of the forwarding drum. 50 Various attempts, all of them involving more or less complicated mechanism, have been made, with the end in view of overcoming these difficulties inherent in the operation of continuous wire drawing machines. 55 It has been proposed to regulate the speed of

the drawing drums automatically by means of the tension of the wire that is being worked, and to this end change speed gearing has been employed in driving the drawing drums, and automatic means, operated 60 by an increase or a decrease in the tension of the wire, are utilized to shift the gears and thereby impart to the drum or drums a greater or less speed, as the case may be. It has also been proposed to drive the drums 65 by belts or cords, and to regulate the speed of said drums by varying the degree of tightness of said belts or cords on their respective pulleys. This regulation is also effected automatically by the tension of the 70 wire that is being worked.

Both of the instrumentalities above referred to involve complicated and expensive mechanism, and furthermore, practice has demonstrated that each is only effective 75 within narrow limits. The positive change speed gearing by which the speed of rotation of one or more drums is suddenly increased or decreased is certain to impart to the wire a more or less violent shock. The 80 belt or cord driven drums of the other mechanism are inefficient and wasteful of power, and are not positive in action. Neither mechanism provides any means for compensating for any considerable resistance to 85 the drawing operation, such as would arise either in the actual drawing of the wire, or in the feeding of the undrawn wire to the machine, and be of such degree as to cause the wire to break. Nor does either mechanism provide any means whereby the machine may be stopped if there is a break in the wire, or if the resistance to the drawing operation rises above a predetermined point. 90 On the contrary, in all machines heretofore used, the machine continues to run even after the wire is broken, until brought to a stop by the operator.

The present invention contemplates, in a continuous wire drawing machine, the elimination of all speed changing means of the character above referred to for the drawing or forwarding drums, and the provision of a series of positively driven drawing drums, having predetermined peripheral speeds, 100 said speeds so calculated as to reduce to a minimum the possibility of slippage between the drum and the wire that is being worked.

It is also proposed, in a machine of such character, to so proportion the successive 110

dies of the machine that the final die through which the wire is drawn merely shapes and smooths the same, whereby the necessity for a heavy draft on the wire in its finally reduced state is avoided, thus minimizing the chances of breakage in the wire at its point of least cross section. And as a simple, inexpensive and reliable means for compensating for any differences in speed between the drums and the wire that is being worked, and also for providing an efficient check or limit upon the tension to which the wire is subjected during the operation of drawing, it is proposed to provide, first, in connection with each drawing drum and die, a movable guide pulley for the wire, normally held, by means of a weight, at its extreme limit of movement, but adapted, when the tension of the wire increases, to move, against the action of its weight in a direction to decrease the length of the wire employed for encircling it and thereby permit a faster feeding of the wire in response to the increased tension; and second, it is proposed to introduce so as to be effective at a point in the wire between said final die and the final drawing drum, where the tension is the resultant of all strains arising in the drawing operation, a positive stop mechanism adapted to stop the operation of the machine when a break in the wire occurs. In addition, there is provided means, in the form of a secondary stop mechanism, interposed in advance of the first drawing or forwarding drum, for relieving the wire undergoing the drawing process of all strains incidental to the unwinding of the undrawn wire from its reel or the feeding of the same to the machine, whereby any considerable resistance arising from such a cause will effect the stopping of the machine.

In order that the invention may be readily understood, the machine will now be described in detail with reference to the accompanying drawings, in which—

Figure 1 is a front elevation of the machine.

Fig. 2 is a top plan view thereof, certain parts being omitted, to render clearer the disclosure of other parts.

Fig. 3 is a detail view, on line 3—3, Fig. 2, illustrating the stop mechanism which is interposed between the final drawing die and drawing drum.

Similar reference characters refer to similar parts in the different figures.

The machine is carried by a frame consisting of spaced parallel members 1, 1, supported by legs 2, 2. Journaled in bearings 3, 3, on the frame members 1, 1, and extending transversely of said frame members, is a main drive shaft 4. The said shaft 4 is extended beyond the rear frame member 1 and is supported in a bearing 3' carried by a bracket 1' on said member, and this extended

portion of the shaft 4 is provided with a fast pulley 5 and a loose pulley 6, either of which is adapted to be driven by a belt 7 connecting with a source of power, not shown. The belt 7 is adapted to be shifted from one pulley to the other, by means of a shifting fork 8, which is operated by mechanism to be hereinafter described.

Suitably spaced apart along the members 1, 1 are the transverse shafts 9, 9', 9² and 9³ which are supported in bearings carried by said members 1, 1, and which carry drawing drums 10, 10', 10² and 10³ respectively, on portions thereof extending outwardly from the front member 1. The shaft 9 carries a gear 11 which is in mesh with a pinion 12 carried by the main drive shaft 4, whereby said shaft 9 is positively rotated at a predetermined speed; and each of the succeeding shafts 9', 9² and 9³ is positively driven from the one next preceding by means of sprocket gearing indicated as a whole respectively by the numerals 13, 13' and 13². The drums 10, 10', 10² and 10³ are identical in size, but the sprocket gearing between the shafts 9, 9', 9² and 9³ is so proportioned as to rotate each drum at a predetermined peripheral speed in excess of the predetermined peripheral speed of the drum next preceding, for a purpose which will herein-after appear.

Carried by the shaft 9² is a bevel gear 14 which meshes with a bevel pinion 15 carried by a vertical shaft 16, directly under the shaft 9² and supported by means of a thrust bearing 17. The shaft 16 drives a vertical shaft 19, supported in a thrust bearing 20 and journal bearing 21, by means of sprocket gearing 22, and said gearing 22 and the bevelled gear wheels 14 and 15 are so proportioned as to give to a vertical drum 23, mounted on the upper end of the shaft 19, a peripheral speed slightly in excess of the peripheral speed of the drawing drum 10³, the said drum 23 constituting the final drawing drum of the series.

Adjacent the forward end of each shaft 9, 9', 9² and 9³, and supported by the front frame member 1, are a number of upright standards 24, 24', 24² and 24³, the same being connected at their upper ends by a longitudinal brace 25. Each upright is recessed as at 26 throughout a major portion of its length and the walls of said recesses form guides for slides 27 which have journaled thereon guide pulleys 28. To each slide is attached a rope or chain 29, passing over a pulley 30 journaled on the brace member 25, and having on its other end a weight 31. The weights normally serve to keep the slides carrying the guide pulleys at their extreme uppermost positions. However, when the wire at any point in the drawing operation is subject to unusual tension or strain, the lowering of one or more of the

pulleys 28, by draft on the wire passing thereover, will automatically compensate for such strain.

At that end of the machine at which the wire is introduced, the front member 1 is provided with a horizontal guideway 32, on which is adapted to reciprocate a slide 33 carrying a pulley 34. Above said guideway and in the same vertical plane as the pulley 34 is located a pulley 35 carried on a member 36, which also is provided with a guiding aperture 37 for the wire. The wire to be drawn is taken from a reel 38, journaled on a bracket 38' at the end of the machine, is passed under and around pulley 34 and over pulley 35 through aperture 37 and is given a number of turns around the first drawing drum 10. From here it is carried up over the sliding pulley 28 and down through the first die box and die plate, in advance of the drawing drum 10'. The several die boxes 39 are mounted on brackets 40 extending from the front member 1, and each carries a guide pulley 41 under which the wire is passed prior to its passage through a die 42, in the forward end of the box. In each successive box of the series, the dies 42 are gradually reduced in size, whereby the wire drawn therethrough is gradually elongated and, for this reason, the peripheral speeds of the several drawing drums are gradually increased from the drum 10 to the drum 10'. Prior to its passage through each die 42, the wire is guided over the corresponding guide pulleys 28 and 41 until it ultimately reaches the final die box 39, which is similar to the preceding die boxes of the series, but is mounted adjacent the vertical drum 23, so that the wire as it is drawn through the shaping die 43 thereof is tangential to the periphery of said drum, and is wound thereon preparatory to being spooled in its final state.

The means by which the spooling is effected will now be described. Mounted in bearings suspended from the members 1 is a transverse shaft 44, which is rotated from the shaft 9' by means of pulleys 45 and 46 and a belt 47. The said shaft 44 is provided intermediate its ends with an intersecting right and left handed screw grooving 48, in which is adapted to travel a member 49 pivoted in a box or sleeve 50 which surrounds the shaft. The box 50 is connected by a link 51 to an intermediate point of a lever 52, pivoted at its lower end 53 and having at its upper end a slotted connection with a horizontally disposed bar 54 slidable transversely of the machine in guides 55. The rotation of the shaft 44 causes the box 50 to reciprocate thereon by reason of the alternate reversals of movement imparted to the pivoted member 49 at each end of the grooving 48. At its front end the bar 54 carries a pair of rolls 57, between which

the wire is led from the drum 23 and thence onto the spool 58 detachably carried by the shaft 59, said shaft being mounted in bearings 60 on the members 1, 1, which bearings 60 also carry the guides 55 for the reciprocating bar 54. The shaft 59 is rotated at a predetermined speed by means of a belt 61 passing over pulleys 62 and 63 on the shaft 9' and on shaft 59 respectively, so proportioned that the peripheral speed of the spool is approximately equal to the peripheral speed of the drum 23. The reciprocation of the bar 54 is timed so as to guide the wire carried by its rolls 57 in even layers on the rotating spool.

Pivoted on a bracket 64, secured to the front member 1 is a bell crank lever 65 having one arm thereof 66 inclined downwardly and forwardly, and pivotally connected to one end of a bar 68, which bar at its other end is slidably supported in a slot 69 of a bracket 70 carried by the frame. The bar 68 has a collar 71 secured thereto for a purpose which will presently appear. A lever 72, pivoted at its lower end 72' to a bracket in the floor, extends upwardly, and adjacent the bar 68 is enlarged in cross section as at 73, and formed with an aperture 73' which loosely encircles the bar 68 between the collar 71 and the bracket 70. When the machine is running, the lever 72 is in the position shown in Figs. 1 and 2, with its upper end above the bar 68 engaged by a notch 74 in a catch lever 75, pivoted on the top of the bracket 70 and passing behind said lever 72.

Secured to the bottom of the last die box is a bracket having a vertical arm 76, in which is journaled a pin 77 carrying a weighted member 78 in the form of a bell crank. The edge of the weighted arm thereof rests lightly against the wire as the same passes from the final die 43 to the drum 23. The other arm of the bell crank 78 is pivotally connected to one end of a link 80, which link at its other end is pivoted to the catch lever 75. Upon the breaking of the wire at this point, which is its point of smallest cross section, the weight 78 will swing downward, and through link 80 will withdraw the catch lever 75 from its engagement with the lever 72. Upon the release of lever 72, a spring 81 secured at one end to the lever and at the other end to a fixed bracket or hook 82 on the frame, serves to carry said lever and with it the bar 68, through the medium of the collar 71, to the left, in Fig. 2, whereby the other arm 67 of the bell crank 65 will be moved rearwardly. Said arm 67 has a pin and slot engagement with one end of a reciprocating rod 83, slidable in ways 84, 84, carried by the frame, the other end of said rod having secured thereto, by means of a standard 85, the belt fork 8. Through the me-

dium of the above described mechanism, the belt 7 is shifted onto the loose pulley when the wire breaks at the point described, and there is thus provided a mechanism for positively stopping the action of the machine when such breakage occurs.

Secured to the slide 33, which carries the pulley 34, is a chain 86 which passes over the pulley 87, journaled on the frame and carries on its other end a weight 88. A heavy spiral spring 89, is hung loosely with one end attached to the slide 33 and the other end to the end of the bar 68 where the latter is joined to the bell crank lever arm 66. When there is any resistance to the unwinding of the wire from the reel 38, or any resistance to the travel of said wire at any point in advance of the drawing drum 10, the slide 33 will be drawn to the left in Fig. 2, in opposition to the pull of weight 88, and if the resistance be strong enough so as to carry the slide any considerable distance to the left, the slack of the spring 89 will be taken up, and finally the bar 68 will be drawn to the left by said spring so as to shift the belt fork 8 and stop the drawing process. The guideway 32 is made long enough so that the above described shifting of the belt fork 8 is effected when the slide 33 has moved to the left to a point about midway the length of said guideway. Even after the machine is disconnected from the source of power, it may continue to operate for a short time due to the inertia of the moving parts, and any tension on the wire caused by such operation is compensated for by a further movement of the slide 33 to the left along said guideway, against the pull of spring 89, thereby relieving the wire of undue strain.

It is to be particularly noted that the stop mechanisms act entirely independently of one another, although both act to move the

bar 68 to the left. When the secondary stop mechanism performs its function the bar 68 is moved without affecting the position of the lever 72, which remains in engagement with the catch lever 75. The machine is started by moving the bar 68 to the right, to the position shown in Fig. 2, by means of a hand lever, not shown, whereby the lever 72 will also be carried to the right through the medium of the collar 71.

I claim:

1. In a continuous wire drawing machine, the combination with a series of parallel shafts, of means for positively driving each of said shafts at a constant speed having a fixed and unvarying relation to the speed of every other shaft, a drawing drum, positively attached to each of said shafts and rotating at the speed of its attached shaft, a series of dies alternating with said drums, and a tension relieving means interposed between each drum and the next succeeding die.

2. In a continuous wire drawing machine, the combination with a series of parallel shafts, of means for positively driving each of said shafts at a constant speed having a fixed and unvarying relation to the speed of every other shaft, a drawing drum positively attached to each of said shafts and rotating at the speed of its attached shaft, a series of dies alternating with said drums, and a tension device comprising a slidably weighted pulley interposed between each drum and the next succeeding die.

Dated this twenty-eighth day of February, 1917.

JAMES P. DOOLEY.
